UNITED STATES PATENT OFFICE.

FRANK W. BROOKE, OF PITTSBURGH, PENNSYLVANIA.

BAR-HEATING FURNACE.

Application filed April 14, 1926. Serial No. 101,927.

It is the object of the invention to provide a furnace for heating bars, slabs or billets for rolling, in which the heat will be utilized to the maximum extent and the bars will be 5 uniformly heated as well. A further object is to provide improved means for feeding bars to a heating furnace, and means for supporting them in proper position therein.

In the accompanying drawings Figure 1 10 is a longitudinal vertical section of a furnace embodying the invention, employed for the so-called pair-heating of sheet or tin-plate bars, the section being taken in the plane of the central line I—I of Figure 2. Figure 2 15 is a sectional plan view taken on the horizontal plane of the line II—II of Figure 1. Figure 3 is a cross-section on the line III—III of Figure 1, and Figure 4 is a cross-section on the line IV—IV of Figure 1.

20 The furnace is shown in the drawings as provided with a combustion-chamber 1 for heating by means of coal, using a standard form of stoker, the flame and products of combustion flowing over the bridge-wall 2 into the heating-chamber 3, and thence 25 through the heating-chamber and out through the flues 4, 4, at the opposite or rear end of the heating-chamber, and into the stack-flues 5. But the character of fuel employed and the manner of its introduction 30 into the heating-chamber are not material to the invention.

The bars or billets being heated are caused 35 to pass through the heating-chamber 3 on ways which are elevated above the floor 6 of the chamber, with the space beneath the ways in open communication with the body of the chamber. These ways preferably consist of hollow water-cooled skid-pipes 7 of 40 well known form which are laid in the top surfaces of blocks 8 mounted on pedestals 9 arranged at intervals in rows longitudinally of the chamber. Thus a pair of the longitudinal skid-pipes 7 constitutes a track 45 through the chamber for the bars or billets. It is also preferred that the primary skid-pipes 7 shall terminate within the chamber at a point somewhat beyond its longitudinal center, and that the length of the track shall 50 be completed by another pair of supplemental skid-pipes 7^a, thus facilitating the removal and replacement of a damaged or worn section of the track. In Figure 1 of the drawings the major portion of the track, 55 consisting of the skid-pipes 7, is horizontal,

while the terminal portion, consisting of the skid-pipes 7^a, is inclined upwardly toward the rear end of the chamber, this arrangement being considered of advantage, though not essential, in the so-called pair-heating of 60 bars as shown, which are arranged on the track transversely of the chamber, and standing on their longitudinal edges with their flat faces contacting with adjacent bars. If desired the bars can be withdrawn or discharged through a suitable opening through 65 the rear end-wall 10 of the furnace, but it is preferred in the pair-heating furnace shown to provide the discharge-opening 11, having the door 12, in the side-wall of the furnace 70 adjacent to the end-wall.

In the heating-chamber the space 13 underneath the bars on the track is in open communication with the body of the heating-chamber through the openings 14 between the pedestals 9. In order to draw active currents of the heated products of combustion around and underneath the bars, flue-ports 15 are formed in the floor 6 of the chamber beneath the track and are connected to a flue 16 underneath the floor, the latter opening into the stack-flue 5. Thus not only is there always maintained the main current of the products of combustion 75 above the bars from the front to the rear 80 of the heating chamber, but commencing at the front of the chamber and throughout its length active currents of high heat intensity are caused to flow down around and beneath the bars, thus subjecting the bars equally on 85 all exposed surfaces, and throughout their travel, to immersion in an active homogeneous bath of heat of substantially equal intensity in any given cross-sectional zone taken transversely of the heating-chamber. 90 The bars are thus effectively heated with the maximum uniformity attainable in furnaces 95 of this type.

For controlling in a measure the flow of the currents of heated products, the ports 15 100 may be individually provided with dampers 17, having operating rods 18 passing through the furnace structure, as shown in Figure 3.

The bars are charged into the furnace, in the relative arrangement shown and above 105 pointed out, through the opening 20 in the front end-wall 21, provided with a vertically sliding door 22. The reciprocable pusher or charging-head 23 may be operated by any suitable means, various types of which are 110

well known, but it is preferred to employ for that purpose the improved mechanism shown in the drawings.

The motor 24, through the pinion 25 on its armature shaft, drives the toothed wheel 26, having on its shaft 27 the worm 28. The worm 28 meshes with the worm-wheel 29, having on its shaft 30 the opposite pinions 31, which respectively mesh with 10 and drive the opposite toothed wheels 32. Outside the wheels 32 are pivoted the lower ends of rocker arms 33, the upper ends of which are respectively connected by links 34, with the opposite ends of the head 23, 15 and meditately connected by links 36 with crank-pins 37 carried by the wheels 32. Thus the motor 24, while running in one direction, operates through the described connections to cause the reciprocation of the 20 head 23 into and away from the furnace opening 20, in a predetermined range of movement. The reversals of the movement of the head 23 being thus accomplished automatically, the usual stops and reversing 25 switches are done away with.

For retaining the row of bars in place in the heating-chamber and preventing them from falling backwardly there is provided a suitable latch or support which is preferably automatic in operation. The preferred latch, which is believed to be new, and which is a part of the present invention, comprises a head 38 mounted on the outer end of the bent arm 39, which projects 30 inwardly and is pivoted medially at 40 underneath the heating-chamber. A weight 41 is carried on the inner end of the arm, and the head 38 works through a slot or recess 42 in the sole-plate 43. The inner 45 face of the head 38 is shaped to support the bars in upright or other desired position, and its body portion slopes outwardly and downwardly in an inclined outer face 44. When the bars are pushed into the furnace 50 the head 38 is caused to move downwardly and outwardly on the pivot 40 as a center and below the face of the sole-plates 43, and it is held down until the outermost bar has passed the apex of the inclined face 44. 55 Then as the pusher-head 23 is withdrawn, the weight 41 causes the upward and inward movement of the bar-supporting head 38 into supporting contact with the rear face of the outermost bar, thus holding the entire row of bars from falling backwardly. The arcuate movement of the head 38 is free, and there is no scraping or frictional binding between the head and the bars, as would take place, for instance, if the head 60 38 were moved in a vertical path.

The lower edge of the door 22 has a slot 45 of suitable form to fit the head 38, so that

the front opening 20 of the furnace may be kept entirely closed except only during the charging of the bars.

It will be understood that the present invention, in part at least, may be employed in furnaces for heating billets, slabs and other metallic bodies, as well as what are known technically as sheet-bars. Therefore 70 the appended claims are directed to furnaces for heating bodies of metal which may be generically called bars, and of various forms and bulk.

I claim as my invention:

1. In a bar-heating furnace, a heating chamber having a fuel inlet at one end and an outlet for the products of combustion at its opposite end, a bar support elevated above the floor of the chamber and extending from end to end thereof with the space beneath said support in lateral communication with the body of the chamber, and a series of outlet ports opening through the floor of the chamber beneath the bar support.

2. In a bar-heating furnace, a heating chamber having a fuel inlet at one end and an outlet for the products of combustion at its opposite end, a bar support elevated above the floor of the chamber and extending from end to end thereof with the space beneath said support in lateral communication with the body of the chamber, a series of outlet ports opening through the floor 95 of the chamber beneath the bar support, and means for controlling the flow of products of combustion through said floor outlet ports.

3. In a bar-heating furnace, a heating chamber having a fuel inlet at one end, a bar support elevated above the floor of the chamber and extending from the fuel-inlet end to the opposite end thereof with the space beneath said support in lateral communication with the body of the chamber, and a series of outlet ports opening through the floor of the chamber beneath the bar support.

4. In a bar-heating furnace, a heating chamber having a floor, a fuel inlet at one end of the chamber and an outlet for the products of combustion at its opposite end, a track elevated above the floor of the chamber and extending from end to end thereof with the space beneath said track in lateral communication with the body of the chamber, a flue beneath the floor of the chamber, and a series of outlet ports opening through the floor of the chamber beneath the track and connected to said flue.

In testimony whereof I have hereunto set my hand.

FRANK W. BROOKE.
